UNITED STATES PATENT OFFICE

KARL HATCH, OF ONEIDA, NEW YORK, ASSIGNOR TO ONEIDA COMMUNITY, LIMITED,
OF ONEIDA, NEW YORK, A CORPORATION OF NEW YORK

DESIGN FOR AN EMBLEMATIC TROWEL OR SIMILAR ARTICLE

Application filed December 31, 1931. Serial No. 42,335. Term of patent 3½ years.

To all whom it may concern:

Be it known that I, KARL HATCH, citizen of the United States, residing at Oneida, county of Madison, State of New York, have invented a new, original, and ornamental Design for an Emblematic Trowel or Similar Article, fully described and represented in the following specification and the accompanying drawing, forming a part of the same, in which

The essential feature of the design is the ornamentation and other matter upon the handle and blade.

I claim:

The ornamental design for an emblematic trowel or similar article as shown and described.

In witness whereof I have hereunto set my hand.

KARL HATCH.
